UNITED STATES PATENT OFFICE.

JOHN B. SIDEBOOTHAM, OF PHILADELPHIA, PENNSYLVANIA.

DESIGN FOR TAPE.

SPECIFICATION forming part of Design No. 29,457, dated October 4, 1898.

Application filed February 3, 1898. Serial No. 669,016. Term of patent 14 years.

To all whom it may concern:

Be it known that I, JOHN B. SIDEBOOTHAM, a citizen of the United States, residing at Philadelphia, (Frankford,) in the county of Philadelphia, State of Pennsylvania, have invented and produced a new and original Design for Tape; and I do hereby declare the following to be a full, clear, and exact description of the invention, such as will enable others skilled in the art to which it appertains to make and use the same.

My invention, which relates to a new and original design for plain and fancy tape, is exhibited in the accompanying drawing, which shows in top plan view a piece of tape fabric embodying the design, *a* indicating the individual strands of the tape.

As shown in the drawing, the material or

essential feature of the design is the form and arrangement of the longitudinal strands 20 thereof, which are flat and of wavy or zigzag contour, ranged side by side, so as to give the appearance of fitting the one within the other, except along the longitudinal edges, which are substantially straight, so as to give 25 the tape as a whole the appearance of a straight flat band.

Having thus described my design, what I claim is—

The design for tape, as shown and described. 30
In testimony whereof I affix my signature in presence of two witnesses.

JOHN B. SIDEBOOTHAM.
